UNITED STATES PATENT OFFICE

2,682,035

LINEAR FREQUENCY SHIFT KEYING
CIRCUIT

Elmer W. Schmittek, Cedar Rapids, Iowa, assignor
to Collins Radio Company, Cedar Rapids, Iowa,
a corporation of Iowa

Application October 26, 1950, Serial No. 192,273

4 Claims. (Cl. 332—29)

1

This invention relates in general to frequency shift keying apparatus.

It is an object of this invention to provide a frequency shift keyer which may be varied in frequency in a linear manner with respect to the magnitude of a controlling voltage.

Another object of this invention is to provide a linear frequency shift keyer that feeds back a reactive component of a voltage to a master oscillator to vary its frequency linearly with respect to a control voltage.

Still another object of this invention is to provide a linear frequency shift keyer which makes use of phase shifters and feedback therefrom to change the frequency of the oscillator.

A feature of this invention is found in the provision for a phase shifting circuit which receives the output of an oscillator, a balanced clipper which has its clipping level varied in response to a control voltage, and a feedback supplied from the clipper to the oscillator for keying the oscillator in a linear manner with respect to magnitude of a keying voltage.

Further objects, features, and advantages of this invention will become apparent from the following description and claims when read in view of the drawings, in which:

Figure 1 is a wiring diagram of the linear frequency shift keying apparatus of this invention; and,

Figure 2 is a schematic diagram of the linear frequency shift keying apparatus.

Figure 1 shows an L-C controlled oscillator comprising a tube V₁, the inductance L₁, and capacitance C₁. The frequency of oscillation of the oscillator is determined by the values of L₁ and C₁, which may be variable if desired. The output of the oscillator appears across R₁ which is in the plate circuit of tube V₁. The plate 10 of tube V₁ is connected to a phase shifter comprising a capacitor C₂ and resistors R₂ and R₄. The opposite side of resistor R₂ is connected to ground. A mid-point between C₂ and R₂ is connected to the cathode 11 of one-half of a double diode V₂ which comprises a clipper circuit. The other cathode 12 of the tube V₂ is connected to a second phase shifter circuit comprising condenser C₃ and resistor R₅. The plates 13 and 14, respectively, of the tube V₂ are tied together and connected to a resistor R₃ which has its opposite side connected to a terminal 16. A condenser C₄ is connected between terminal 16 and ground. A third tube V₃ has its control grid 17 connected to the point between C₃ and R₅ and its cathode 18 is connected to ground through the resistance R₆. Its plate 55

2

19 supplies a feedback to the controlling tank circuit L₁ and C₁ through a coupling condenser C₅. The plate 19 is also connected to B+ through the resistor R₇.

5 In operation the output of tube V₁ is supplied to the clipper V₂ through the coupling condenser C₂. Resistors R₂ and R₄ are equal and therefore the clipper is balanced to ground. A control voltage is supplied between ground and terminal 16 to adjust the clipping level of the clipper. The output of the clipper is amplified by the isolation amplifier V₃ and fed back to the tank circuit comprising L₁ and C₁. The components of the phase shifting circuits comprising C₂, C₃, R₂, R₄ and R₅ are chosen so that they will shift a signal of the carrier frequency by 90 degrees. The tubes V₁ and V₃ shift the incoming signals the usual 180 degrees respectively or one full cycle, and thus, the total phase shift of the signal fed back to L₁, 10 C₁ is 360 plus 90 degrees or 450 degrees. The adding of a signal shifted 450 degrees (same as 90 degrees) is to present an effective increase in capacitance and this causes the frequency of the oscillator to change. The amount of the frequency change depends upon the amount of capacitance fed back to the tank circuit and this in turn depends upon the control voltage supplied to terminal 16.

Figure 2 illustrates schematically an oscillator 21, a 90 degree phase shift network 22, a clipper 23 and an isolation amplifier 24. A control voltage varies the bias on the clipper and thus regulates the amplitude of the output in a linear manner. Clippers of this nature are well known to those skilled in the art, and any type which performs this function may be used.

30 A use for this invention is to reproduce a picture electronically. If a photoelectric cell is used to measure the varying intensity of a picture, the output of the cell might be used as the control voltage supplied to the terminal 16 to vary the frequency of the oscillator linearly. If the oscillator is used as a transmitter, it will transmit a frequency modulated signal which carries the information as to the density of the picture at various points. This information can be detected at a receiver and the picture reconstructed. The linear relationship between the density of the picture and the frequency shift makes possible reproduction. This example is given to show one way in which the apparatus of this invention might be used. It is to be understood, of course, that there are other uses for the invention.

35 The control voltage regulates the amplitude of the feedback signal and thus regulates the

amount of frequency shift which occurs in the oscillator output. Thus, means are provided for shifting the frequency of a controlled oscillator in linear manner in response to a control voltage.

The exact types of L-C oscillator, clipper or amplifier are not critical. The clipper may be a shunt type as well as the series type. The in-phase shift networks may be capacitive or inductive.

Values of the various components may be, for example:

C₂—10 micromicrofarads
 C₃—100 micromicrofarads
 C₄—0.01 microfarad
 C₅—100 micromicrofarads
 B₁—180 volts positive
 B₂—100 volts positive
 R₁—10,000 ohms
 R₂—47,000 ohms
 R₃—220,000 ohms
 R₄—47,000 ohms
 R₅—22,000 ohms
 R₆—1,000 ohms
 R₇—100,000 ohms
 V₁—6BA6 Tube Type
 V₂—6AL5 Tube Type
 V₃—6BA6 Tube Type

Although this invention has been described with respect to particular embodiments thereof it is not to be so limited as changes and modifications may be made therein which are within the full intended scope of the invention as defined by the appended claims.

I claim:

1. Means for varying the frequency of a frequency shift oscillator having a tank circuit comprising, a first degree phase shifter receiving an output of said oscillator, a clipper circuit receiving the output of said first phase shifter, a control voltage supplied to said clipper to vary its clipping level in response to a control signal, a second phase shifter receiving the output of said clipper, and the total phase shift of the first and second phase shifters being equal to 90

45 degrees, and the output of said second phase shifter furnished to the tank circuit of said oscillator.

2. Means for varying the frequency of an oscillator having a tank circuit comprising, phase shifting means receiving the output of said oscillator, clipping means receiving the output of said phase shifting means, a control voltage source supplying an output to the clipping means to vary its bias in response to the value of the controlled voltage and an output of said clipping means supplied to said oscillator.

3. Means for linearly shifting the frequency of a resonating-element-controlled oscillator comprising, 90 degree phase shifting means receiving the output of said oscillator, clipping means receiving the output of said phase shifting means, a control voltage supplied to said clipping means to vary the clipping level, keying means producing the control voltage and supplying it to the clipping means, and feedback means supplying an output of said clipper to the resonating element of the oscillator.

4. Means for linearly varying the frequency of an L-C tank circuit controlled oscillator comprising, phase-shifting means receiving an output of said oscillator to shift it ninety degrees, a clipping circuit receiving the output of said phase-shifting means, control means supplying a bias to said clipper to vary the clipping level, and the output of said clipper being connected to the L-C tank circuit to vary its resonant frequency.
